[57] CLAIM

The ornamental design for a remote control for electrical equipment, as shown and described.

DESCRIPTION

FIG. 1 is a top plan view of a remote control for electrical equipment showing my new design;

FIG. 2 is a bottom plan view thereof;

FIG. 3 is a left side elevational view thereof, the opposite side being a mirror;

FIG. 4 is a rear elevational view thereof; and,

FIG. 5 is a front elevational view thereof.

*FIG. 1**FIG. 2**FIG. 3**FIG. 4**FIG. 5*
